[57] CLAIM

The ornamental design for an article lifter, as shown and described.

DESCRIPTION

FIG. 1 is a front perspective view of my article lifter; FIG. 2 is a rear perspective view of the apparatus depicted in FIG. 1;

FIG. 3 is a rear perspective view of a second embodiment of my invention;

FIG. 4 is a rear perspective view of a third embodiment of my invention;

FIG. 5 is a rear perspective view of a fourth embodiment of my invention;

FIG. 6 is a rear perspective view of a fifth embodiment of my invention;

FIG. 7 is an exploded rear view of a sixth embodiment; and,

FIG. 8 is a front perspective view of a seventh embodiment, the rear view being like the FIG. 2 view.

The opposite view of the L-shaped base plate in FIGS. 3—7 is identical to the FIG. 1 view and the bottom surface of the base plate is flat.

1 Claim, 4 Drawing Sheets

FIG. 8

FIG. 7
